Primary Examiner—Robert M. Spear[57] **CLAIM**

The ornamental design for a vinyl license plate, as shown and described.

DESCRIPTION

FIG. 1 is a front right perspective view of a vinyl license plate showing my new design.

FIG. 2 is a front view of license plate showing my new design. Shading in FIG. 2 illustrates reflective vinyl.

FIG. 3 is a rear view showing self-adhesive and slits for ease of application.

FIG. 4 is a top or bottom view; and,

FIG. 5 is a left or right view.

In the drawings, the broken lines are for illustrative purposes only and form no part of the claimed design.
